UNITED STATES PATENT OFFICE.

ELMER E. WILKINSON AND SAUL ARONSON, OF BROOKLYN, NEW YORK, ASSIGNEES, BY
MESNE ASSIGNMENTS, TO THE SILENT MOTOR CORPORATION, OF BROOKLYN, NEW
YORK, A CORPORATION OF NEW YORK.

ADJUSTABLE BEARING FOR SPRING MOTORS.

Application filed September 4, 1920. Serial No. 408,151.

To all whom it may concern:

Be it known that we, ELMER E. WILKINSON, a citizen of the United States, and a resident of the city of New York, borough of Brooklyn, county of Kings, and State of New York, and SAUL ARONSON, a citizen of the United States, and a resident of the city of New York, borough of Brooklyn, county of Kings, and State of New York, have invented certain new and useful Improvements in Adjustable Bearings for Spring Motors.

Our invention relates generally to adjustable bearings and, although adapted for use wherever shaft bearings are required to be adjusted, is particularly applicable to spring motors used in operating phonographs.

It is a common experience in assembling the parts of a spring motor, that the governor shaft requires careful adjustment in order to bring about the proper engagement between the worm on the shaft and the worm-gear on the turntable shaft. No matter how carefully the bearing holes for the governor shaft are drilled in the casting of the motor, it is practically impossible to get them so perfect that the worm and worm-gear referred to will be in correct mesh without adjustment of the governor shaft. For this purpose eccentric bearings have in some instances been employed for the governor shaft, but it seems to be next to impossible to so adjust the two bearings as to bring them into perfect alignment, with the result that the governor shaft would run slightly askew. While such a small disarrangement of the governor shaft might in some instances not interfere with its proper connection with the turntable shaft, it would nevertheless cause the shaft to run unevenly in its bearings.

To overcome these and other objections, we have provided an adjustable bearing which automatically takes care of any disalignment that may have to be made in the position of the governor shaft to effect the proper connection between the worm on that shaft and the worm gear on the turntable shaft, and which will allow the governor shaft to run in full bearings in any of its adjusted positions.

Another object of our invention is to provide an adjustable bearing for the up-

per end of the turntable shaft, so as to 55 take up the play which may occur at that end of the shaft during the operation of the motor.

To explain the principle of our invention, we have illustrated a preferred embodiment in the accompanying drawings in which—

Fig. 1 shows a portion of a phonograph spring motor containing the features of our invention; 65

Fig. 2 is an enlarged fragmentary view in cross-section approximately on line 2—2 of Fig. 1, showing one of the adjustable bearings for the governor shaft;

Fig. 3 is an enlarged end view of one of 70 the bearings;

Fig. 4 is an enlarged view of the hollow ball contained in the bearing and into which extends the end of the shaft; and

Fig. 5 is a detached view in cross-section 75 of a portion of the adjustable bearing for the turntable shaft.

As our invention is applicable to spring motors of various types, we have not deemed it necessary to illustrate any particular construction of motor. 80

For the purpose of explaining our invention, we need only say that the parts of the motor are supported in a framework or casting indicated as a whole by A, which 85 is secured to the underside of the top board 1 of a phonograph cabinet. The vertical turntable shaft 2 is supported in the casting A and is adapted to be driven by the motor springs in a manner well understood 90 by those skilled in the art. The speed of the turntable shaft 2 is controlled by the usual type of governor indicated as a whole by G. As the construction and operation of this form of governor are well known to the 95 skilled mechanic, no details of description are necessary. We need only say that the governor shaft 3 has a worm 4 which is in mesh with the worm-gear 5 of the turntable shaft 2. The governor shaft 3 is supported 100 in bearings indicated as a whole by B, which are mounted in the standards 6 of the casting A.

Owing to the peculiar formation of the worm 4 and the worm gear 5, it is necessary 105 to have the governor shaft 3 in just the proper position to produce a smooth and noiseless engagement between the worm and

the worm-gear. For this it is nearly always necessary to adjust the governor shaft laterally after the parts have been assembled.

We will now describe the bearings by 5 which this adjustment of the governor shaft is carried out. As the two bearings B are alike in construction and function, we need only describe one of them.

Each bearing consists of a cylindrical 10 body portion 7, adapted to fit into a corresponding opening in the standard 6 of the framework A. A set-screw 8, or the like, holds the bearing in adjusted position. At 15 its outer end the body portion 7 is provided with a knurled finger piece 9, by means of which the bearing is easily turned in its opening. From the other end of the body portion 7 extends an eccentric chuck 10 which is screw-threaded on the outside, as 20 indicated at 11 in Fig. 2. The chuck 10 is preferably split at diametrically opposite points, as indicated at 12 in Figs. 2 and 3, for a purpose to be presently explained.

The body portion 7 of the bearing has a 25 hole 13 into which is driven a pin 14. To secure the pin firmly in the hole, we provide a roughened head or enlargement 15 at the inner end of the pin. When the pin is driven in, this roughened head is forced 30 into firm engagement with the wall of the hole 13, whereby the pin is held in position against any possibility of displacement. As seen from Fig. 2, the free or outer end 35 of the pin 14 terminates in the recess or chamber 10^a formed within the chuck. In this recess or chamber is seated a bored ball 16 having a bore 17 for receiving the end 18 of the shaft. The bearing ball 16 is adapted to turn in its seat in the chuck in 40 every direction. In other words, the ball 16 is a universally adjustable bearing. The inner end of the ball 16 rests against the inner end of the chamber 10^a as shown in Fig. 2, so that the ball is always held at 45 the mouth of the chuck ready to receive the end of the shaft. In operation, the ball 16 is stationary, while the end 18 of the governor shaft revolves in the bore 17. The outer end of the pin 14 forms a stop for 50 the inner end of the shaft 3. We prefer to make the ball 16 of a good bearing material, such as phosphor bronze, or the like.

We make the ball 16 a trifle larger than 55 the mouth of the chuck and provide it with a slit 19, as shown in Fig. 4. This produces sufficient resiliency in the ball to allow the same to be snapped into the chuck, and also to permit it to be contracted or squeezed together, when necessary, for the purpose of 60 taking up the wear in the bore 17. For this purpose we provide a cap 20, having interior screw-threads 21 to engage the screw-threads 11 of the chuck 10. As seen from Fig. 2, the chuck 10 is at its outer end 65 formed with a conical portion 10^b adapted

to be engaged by the correspondingly shaped wall 20^b of the cap 20 when the latter is screwed home on the chuck. By screwing the cap 20 tight on the chuck, the wedging action of the wall 20^b on the conical portion 10^b of the chuck contracts the chamber 10^a. The slits 12, previously referred to, render the chuck 10 sufficiently resilient to permit this contraction. By contracting the bearing chamber 10^a, the resilient ball 16 is squeezed together and the bearing hole 17 thereof is made correspondingly smaller. In this simple way, whatever wear may occur in the bore 17 due to the rotating shaft 3 is readily taken up to insure a steady 80 running of the shaft in its bearing. To remove the ball it is only necessary to unscrew the cap 20, whereupon the ball is easily forced out of the chuck by simply inserting the point of a suitable instrument in the bore 17.

It will be seen from Fig. 4 that the slit 19 of the ball 16 is diagonal to the axis of the bore 17. We prefer this construction, because, if the slit 19 were parallel with the bore 17, there will be formed a pair of spaced shoulders or edges parallel with the shaft and that would interfere with the smooth, quiet running of the shaft. This is avoided by slanting the slit as shown, so that the break produced by the slits is not felt by the shaft.

It will thus be seen that we have provided an exceedingly simple and effective bearing for adjusting the supported shaft. After the governor shaft has been so adjusted that the worm 4 and the worm-gear 5 are in proper relation, it is immaterial that the chucks of the two eccentric bearings B are not in axial alignment, for any axial disarrangement of the shaft 3 is automatically compensated by the universally adjustable balls 16. Referring to Fig. 2, if we imagine the shaft 3 being turned out of axial alignment with the axis of the chuck, the bearing ball 16 will roll bodily in the chuck and so give the shaft full bearing in any of its adjusted positions.

It frequently happens in spring motors for phonographs, that the turntable shaft will after a time begin to wobble. That not only interferes with the proper playing of the record, but may affect the worm gear connection between the turntable shaft and the governor shaft. To prevent this wobbling we provide an adjustable bearing for the upper end of the turntable shaft, so that, whenever necessary, the bearing through which the shaft projects may be adjusted to take up the side play of the shaft.

Referring to Fig. 1, it will be seen that the turntable shaft 2 passes through an opening in the plate 22 of the motor casting A. As best seen from the enlarged view of Fig. 5, the opening in the plate 22 consists of

a cylindrical portion 23 and a conical or flaring portion 24. Into this opening fits a bearing member of brass or similar material.

This bearing member, which I have indicated as a whole by P, consists of a screw-threaded cylindrical portion 25 and a flaring or conical portion 26 provided with a slit 27. The member P has a cylindrical bearing opening 28, through which the turntable shaft 2 passes. With the bearing member P co-operates an adjusting member indicated as a whole by R, which is generally cylindrical in form, having an outside polygonal section 29, very much like a hexagonal nut, by means of which the member may be turned, as will be understood. At its lower inner end the member R has screw-threads 30 adapted to enter into engagement with the screw-threads 25 of the member P when the two parts are brought together. It will be clear from Fig. 1, that when the member R, which is in effect a hollow cylindrical nut, is screwed down, the bearing member P will be drawn up into the opening 23-24 of the plate 22. As the flaring portion 26 of the bearing member P is drawn into the flaring opening 24, the bearing opening 28 is contracted an amount proportionate to the movement of the member P. The slot 27 in the flaring portion 26 renders the latter resilient, and so permits this contraction. When, therefore, the operator finds that the turntable shaft 2 is wobbling, he simply gives the cylindrical nut R a slight turn by inserting a wrench over the polygonal section 29, until the bearing opening for the shaft is sufficiently reduced.

The member R performs the additional function of an oil-cup. So that, to keep the bearing well oiled, it is only necessary to pour a little lubricating oil into the hollow nut R, from which it will gradually seep into the bearing opening 28.

While we have thus set forth a specific construction, we would have it understood that we have done so merely to explain our invention and not by way of limitation. It is obvious that the features of our invention may be mechanically carried out in other ways than are shown and described.

What we claim as our invention is:

1. In spring motors for phonographs and the like, an upright turntable shaft, a horizontal governor shaft geared to said turntable shaft and driven thereby, a pair of eccentric bearings for said governor shaft, said bearings being adjustable to regulate the lateral position of the governor shaft in relation to the turntable shaft, and a universally adjustable member carried by each bearing for receiving one end of the governor shaft, said members automatically adjusting themselves to any lateral adjustment of the governor shaft.

60

2. In spring motors for phonographs and the like, an upright turntable shaft, a horizontal governor shaft geared to said turntable shaft and driven thereby, a pair of eccentric bearings for said governor shaft, said bearings being adjustable to regulate 65 the lateral position of the governor shaft in relation to the turntable shaft, and a bored ball carried by each bearing for receiving one end of the governor shaft, said bored balls being universally adjustable in said 70 bearings to maintain a full bearing for the governor shaft in any adjusted position.

75

3. In spring motors for phonographs and the like, a framework or casting for the motor, an upright turntable shaft adapted to be driven by the motor spring and having a worm gear, a horizontal governor shaft having a worm in mesh with said worm-gear, a pair of bearings mounted in said framework for supporting said governor shaft in operative relation to said turntable shaft, said bearings being rotatably adjustable and provided each with a hollow eccentric chuck, and a bored ball mounted in each chuck for receiving one end of the governor shaft, said balls being universally adjustable 80 in the chucks to maintain a full bearing for the governor shaft in any adjusted position.

85

4. As a new article of manufacture, an adjustable bearing comprising a body portion, a chuck extending from said body portion, and a bored bearing ball mounted in said chuck so as to be universally adjustable therein and adapted to receive one end of a shaft, said ball being sufficiently resilient 90 to permit ready insertion and removal of the ball into and from the chuck.

95

5. As a new article of manufacture, an adjustable bearing comprising a body portion, a chuck extending from said body portion and a bored bearing ball mounted in said chuck so as to be universally adjustable therein and adapted to receive one end of a shaft, said ball being split along a line diagonal to the axis of the hole in the ball to 100 permit ready insertion and removal of the ball into and from said chuck.

105

Signed at the city of New York, in the county of New York, State of New York, this 3rd day of September, 1920.

ELMER E. WILKINSON,
SAUL ARONSON.
